SPARK PLUG SCRAPER

Walter I. Scott and Lillian H. Foster,
New Orleans, La.

Application July 24, 1934, Serial No. 736,748

1 Claim. (Cl. 15—104.01)

This invention relates to a scraper especially adapted for removing carbon and like foreign matter from a spark plug which tends to interfere with the efficiency of a spark plug after a period of use in an engine, and has for the primary object the provision of a tool which may be stamped or otherwise made at a low cost and is provided with prong portions having cutting edges to be inserted in the body of a spark plug about the insulator to remove carbon found between the body and the insulator by a simple turning movement of said tool in opposite directions.

With these and other objects in view this invention consists in certain novel features of construction, combination and arrangement of parts to be hereinafter more fully described and claimed.

For a complete understanding of the invention, reference is to be had to the following description and accompanying drawing, in which

Figure 1 is a vertical sectional view illustrating a spark plug with a scraper applied thereto and constructed in accordance with our invention.

Figure 2 is a plan view illustrating the scraper. Figure 3 is an edge view illustrating the same.

Figure 4 is a sectional view taken on the line 4—4 of Figure 2.

Referring in detail to the drawing, the numeral 1 indicates a finger piece preferably constructed of metal of a suitable gage which is cut away, as shown at 2, to form spaced portions 3 terminating into prongs 4. Opposite edges of the prongs are beveled to form cutting edges 5 which cutting edges merge with one another at the free ends or pointed ends of the prongs. The

opposed cutting edges 5 of the prongs are disposed at an inclination or converge towards the cut-away portion 2 of the finger piece so as to conform to the contour of one end of an insulator 6 of a spark plug 7, as shown in Figure 1. In use the prongs are inserted between the tapered end of the insulator 6 and the body portion 8 of the spark plug and by turning the finger piece in opposite directions the cutting edges 5 will remove carbon adhered to the insulator and the inner wall of the body 8.

The portions 3 of the finger piece which merge into the prongs 4 are offset, as shown at 9. The offsets 9 permit the prongs to pass under the negative electrode of the spark plug or that electrode carried by the body 8 of said spark plug. The prongs being able to pass under the electrode referred to permits the entire space between the insulator and the body of the plug to be freed or cleaned of carbon.

The finger piece 1 is apertured for the reception of a key ring or like device.

Having described the invention, we claim:

A scraper comprising a plate providing a finger piece, parallel spaced shanks integral with the plate and formed to provide recesses offset from the plane of the shanks and in the same direction to receive a grounded electrode of a spark plug, and flat spaced prongs integral with and extending in the same direction as the shanks 30 with the outer edges thereof substantially parallel and each tapering towards its free end and having inner and outer cutting edges, said shanks and prongs defining a space to receive an insulator of the spark plug.
